The ornamental design for an atomizer, as shown and described.

DESCRIPTION

FIG. 1 is a front elevational view of a first embodiment of an atomizer;

FIG. 2 is a left side elevational view of the first embodiment of the atomizer;

FIG. 3 is a bottom plan view of the first embodiment of the atomizer;

FIG. 4 is a top plan view of the first embodiment of the atomizer;

FIG. 5 is a first perspective view of the first embodiment of the atomizer;

FIG. 6 is a second perspective view of the first embodiment of the atomizer;

FIG. 7 is a front elevational view of a second embodiment of an atomizer;

FIG. 8 is a bottom plan view of the second embodiment of the atomizer;

FIG. 9 is a top plan view of the second embodiment of the atomizer;

FIG. 10 is a first perspective view of the second embodiment of the atomizer;

FIG. 11 is a second perspective view of the second embodiment of the atomizer;

FIG. 12 is a front elevational view of a third embodiment of an atomizer;

FIG. 13 is a rear elevational view of the third embodiment of the atomizer;

FIG. 14 is a left side elevational view of the third embodiment of the atomizer;

FIG. 15 is a right side elevational view of the third embodiment of the atomizer;

FIG. 16 is a bottom plan view of the third embodiment of the atomizer;

FIG. 17 is a top plan view of the third embodiment of the atomizer;

FIG. 18 is a first perspective view of the third embodiment of the atomizer; and,

FIG. 19 is a second perspective view of the third embodiment of the atomizer.

The broken lines in the drawings depict parts of the atomizer that form no part of the claimed design.
